UNITED STATES PATENT OFFICE.

ROBERT H. BERTRAM, OF DAVENPORT, IOWA.

LEVEL.

Application filed November 11, 1925. Serial No. 68,427.

This invention relates to improvements in leveling apparatus and has for its prime object to provide a level of very sensitive construction and designed to accurately indicate 5 the angular inclination of objects upon which it is placed.

A further object of the invention is the provision of a level of the above character having a graduated dial so as to designate 10 the exact angular inclination of an object from a level or horizontal position.

A still further object of the invention is the provision of a leveling apparatus of compact and durable construction and designed 15 so as to be sold at a reasonable cost.

Other objects and advantages of this invention will become apparent as the description progresses.

In the accompanying drawing forming a 20 part of this specification and in which like numerals are employed to designate corresponding parts throughout the same:

Figure 1 is a front elevation of a fragmentary portion of a level constructed in accordance with my invention,

Figure 2 is a longitudinal sectional view showing the casing structure in elevation,

Figure 3 is a transverse sectional view taken on the line 3—3 of Figure 1,

Figure 4 is a detail perspective view of a 30 member forming a part of an indicating mechanism, and

Figure 5 is a similar view of a complementary member also forming a part of the 35 indicating mechanism.

In the drawing, wherein is illustrated a preferred embodiment of the invention, the numeral 10 generally designates the body or stock of the level. This stock is usually of 40 rectangular formation and preferably constructed of wood or light metal. One or both of the longitudinal edges of the stock are straight edges so that the apparatus may accurately indicate the angular position of 45 the object upon which it is placed. The center of the stock is provided with a counter-sunk chamber 11 extending through the greater width of the stock so as to provide a comparatively thin backing strip 12.

Securely mounted in the chamber 11 formed 50 in the stock 10 is an annular casing 13 designed to provide an enlarged ring 14 at its upper portion of substantially increased diameter. The structure of the casing is arranged so as to snugly fit the counter-sunk chamber formed in the stock and is retained

securely in position therein by means of a pair of oppositely disposed ears 15 apertured for the reception of suitable fastening screws 16. Formed at the center of the casing and projecting outwardly is a bearing sleeve 17 of comparatively small diameter, this sleeve being enclosed at its outer extremity and adapted to fit flush with the rear side of the stock. The forward edge of the casing is arranged 65 so as to be fitted flush with the front side of the stock, the ears 15 being positioned in suitable recesses for this purpose.

Rotatably mounted in the casing and arranged so as to be freely rotatable therein is 70 an indicating mechanism composed of a pair of co-acting relatively movable members. One of the indicating members comprises a tapered frame structure 18 provided at the outer enlarged end with a pair of arcuately 75 formed bars 19, spaced to provide a slot 20 therebetween. The inner reduced end of this frame structure is formed with an adjustable tube 21 of arcuate formation, the outer edge of this tube being split and provided with co-acting parallel ears 22. The bottom ear is provided with an internally screw threaded opening, while the upper ear is provided with a smooth bore of circular formation. This structure permits the connection of a screw 80 23 adapted to project through the openings formed in the ears 22 for adjustable connection of the sleeve, the purpose of which will become apparent as the description progresses. The tapered body of the frame 18 connects with the sleeve 21 by means of V-shaped 85 ribs 24 extending on the upper and lower edges of the sleeve and preferably formed integral therewith. The opposite extremity of the frame 18 is provided with an outwardly 90 projecting pointer 25 formed in the center of the frame so as to designate the angular inclination of the level, as will be described more fully hereinafter.

Mounted in co-acting relation with the 100 frame 18 and arranged so as to provide a highly sensitive indicating apparatus, is a rotatable balance member 26 embodying at one end a substantially U-shaped bracket 27 having the upper and lower parallel projections of tapered formation as at 28 to provide fulcrum points 28'. A longitudinal bar 29 extends laterally from the U-shaped bracket 27 and carries on its outer extreme end a right angular projection in the form of a circular 105 guide pin 30, this member being detachably secured to the end of the bar by a set screw or

in any suitable manner. It will be noted, from Figure 5 of the drawing, that the lower projection of the movable indicating member is provided with a laterally extending pivot pin 31 of preferably circular formation and adapted to rotatably engage the bearing sleeve 17 formed in the casing structure. The members 18 and 26 are assembled by placing the fulcrum points 28^b at the apex of the V-shaped ribs 24 formed on the sleeve 21. The guide pin 30 is then positioned in the arcuate slot 19 and securely fastened to the extension bar 29 of the member 26. This connection provides a delicate balance connection of the movable indicating structure, the pivot pin 31 being rotatably mounted in the bearing sleeve 17 so that the indicator will be readily rotatable and at the same time properly balanced.

20 In order that the pointer 25 may accurately indicate the inclination of the level a tube 32 of arcuate formation is secured in the adjustable sleeve 21, this tube being constructed of glass or metal and adapted to contain a suitable liquid, preferably a solution of mercury and alcohol. The tube is preferably arranged in a radial arc with the indicating pointer so as to effectively balance the frame 18.

An important characteristic of the present invention embodies the provision of a dial 32' to be formed on the outwardly directed flange or shoulder ring 14, this dial being preferably of circular formation and graduated into degrees of angular measurement. With particular reference to Figure 1, it will be seen, that the zero mark on the dial is at the lowest point on the transverse center line through the level mechanism, and the dial is formed with numerals at regular intervals indicating the number of degrees of angular measurement.

In use, the lower longitudinal edge of the level is placed upon the object whose angular inclination it is desired to ascertain and the position of the level stock and casing determined relative to that of the pointer 25. From the foregoing description, it is obvious, that the pointer 25 will be at all times retained in a downward vertically aligned position with the pivot pin. The inclined position of the casing will, therefore, accurately indicate the exact angle of inclination of the surface upon which the level is positioned. The provision of the independently movable indicating structure necessarily forms a delicately balanced pointer designed to indicate the angular measurement to a very accurate degree. The sensitiveness of the indicating apparatus is further increased by the provision of the arcuate liquid tube 32, filled with a mercury solution, and thus having a gravitational effect to balance the pointer. It is therefore apparent that the indicating mechanism will be normally held in a vertically suspended position by the attraction of gravity, while the body of the level may as-

sume various angular positions from a horizontal to a vertical angle.

The upper edge of the casing 13 is provided with an interior shoulder of annular formation adapted to receive thereon a cover 33 removably mounted on the casing and preferably constructed of glass or other transparent material. This cover is rigidly retained in position by a resilient metallic ring 34 adapted to be contracted so as to engage an annular groove formed adjacent the upper edge of the casing and prevent displacement of the cover 33.

This structure provides a durable level of compact structure designed particularly to provide an accurate indicating apparatus of extreme accuracy arranged so as to readily indicate the angular inclination from a level or horizontal position.

It is to be understood that the form of my invention herewith shown and described is to be taken as the preferred example of the same and that various changes as to the shape, size and arrangement of parts may be resorted to without departing from the spirit of the invention or the scope of the subjoined claims.

Having thus described my invention, I claim:

1. An apparatus of the character described comprising a body having a chamber formed therein, a gravity actuating mechanism mounted in the body including a tapered frame member having an adjustable sleeve formed on one end and an arcuate slot formed adjacent the opposite end thereof, a pointer formed on the outer extremity of the frame, a co-acting balance member embodying a U-shaped bracket having a pivot pin formed laterally on one projection thereof adapted to pivotally support the frame member, a longitudinal arm formed integral with the bracket and extending laterally therefrom, a guide pin secured to the outer extremity of the arm adapted to engage the arcuate slot formed in the frame member, and a liquid containing tube secured in position in the sleeve formed on the frame member so as to sensitively balance the gravity actuated mechanism.

2. A level comprising a stock having a counter-sunk chamber in the center thereof, a casing having an enlarged ring adjacent the outer edge securely mounted in the chamber, a bearing sleeve formed in the center of the casing, indicating mechanism pivotally mounted in the casing including a tapered frame having an adjustable sleeve formed on one end thereof and an arcuate slot formed adjacent the opposite end of the frame, a pointer formed adjacent the arcuate slot, a co-acting balance member including a U-shaped bracket, a longitudinal bar extending transversely from the bracket, a guide pin secured on the opposite end of the bar, the said frame being pivotally mounted on the bal-

ance member to provide an accurately balanced indicating mechanism, a pivot pin formed on the balance member engageable with the bearing sleeve formed in the casing, 5 a tube containing liquid secured in the adjustable sleeve so as to balance the frame member, a circular dial formed in the casing graduated to indicate degrees of angular measurement, the dial being arranged in the 10 path of movement of the pointer, and a cover of transparent material removably secured on the casing for enclosing the same.

3. A level indicator of the character described, comprising a balance member including a bar formed at one end to provide a cradle, a laterally projecting supporting pivot pin at one side of said cradle, a fulcrum point on each side of said cradle, a swinging member provided with a pair of 20 bearings each receiving one of said fulcrum points, a pointer carried by said swinging member, means carried by said bar and engaging said swinging member for limiting its

movement and a balance weight carried by said swinging member.

4. A level indicating device, comprising a balance member constituting a relatively long bar having one end enlarged and formed to provide a substantially U-shaped cradle, a pivot pin projection laterally from one side 25 of said cradle, for engagement in a fixed bearing, a fulcrum point formed at each side of said cradle, an open tapered frame formed to provide a guide slot at one side thereof, a pair of substantially inverted V-shaped bearings adjacent the tapered end of the frame each designed to receive one of said fulcrum points to set up a knife bearing between the frame and the balance member, a retaining pin carried by said bar and engaging in said 30 guide slot, a pointer carried by said frame, an arcuate tube and means for securing the tube to said frame.

In testimony whereof I affix my signature.

ROBERT H. BERTRAM.
